UNITED STATES PATENT OFFICE

153,853

DESIGN FOR A RECEPTACLE FOR FIRE EXTINGUISHING GRENADES

Arthur Cizek, Denver, Colo., assignor to Red
Comet Incorporated, Littleton, Colo., a corpora-
tion of Colorado

Application November 12, 1947, Serial No. 142,491

Term of patent 14 years

(Cl. D16—2)

To all whom it may concern:

Be it known that I, Arthur Cizek, a citizen of the United States, residing in the city and county of Denver and State of Colorado, have invented a new, original, and ornamental Design for a Receptacle for Fire Extinguishing Grenades, of which the following is a specification, reference being had to the accompanying drawing, forming part thereof.

In the drawing:

Fig. 1 is a perspective view of a receptacle for fire extinguishing grenades showing my new design;

Fig. 2 is a top plan view thereof drawn to a reduced scale for convenience of illustration; and

Fig. 3 is a front elevation thereof drawn to reduced scale for convenience of illustration.

I claim:

The ornamental design for a receptacle for fire extinguishing grenades, as shown and described.

ARTHUR CIZEK.
